UNITED STATES PATENT OFFICE.

JOHN S. DEAN, OF EDGEWOOD PARK, PENNSYLVANIA, ASSIGNOR TO WESTINGHOUSE ELECTRIC & MANUFACTURING COMPANY, A CORPORATION OF PENNSYLVANIA.

SPRING-TENSION MEANS FOR BRUSH-HOLDERS.

1,381,289.

Specification of Letters Patent. Patented June 14, 1921.

Application filed September 17, 1920. Serial No. 410,882.

To all whom it may concern:

Be it known that I, JOHN S. DEAN, a citizen of the United States, and a resident of Edgewood Park, in the county of Allegheny and State of Pennsylvania, have invented a new and useful Improvement in Spring-Tension Means for Brush-Holders, of which the following is a specification.

My invention relates to brush-holders and 10 it has particular relation to spring tension devices therefor.

Heretofore, great difficulty has been encountered in obtaining the necessary degree of rotary adjustment of the stud shaft upon 15 which the brush spring is mounted.

It has been customary to rotatably mount the stud shaft in the brushholder frame and to maintain it therein without displacement by means of cotter pins which extend 20 through the bearing portion of the brushholder and the shaft. In order to obtain a variety of rotary adjustments of the shaft, it has been customary to provide both the bearing elements and the shaft with a plurality of intersecting radial apertures, different ones of which were brought into alignment according to the degree of tension desired.

It has, however, been observed that by 30 reason of the relatively small diameter of the shaft, only a comparatively few apertures may be provided in the same plane without materially weakening the shaft.

One of the objects of my invention is to 35 provide a device of the character described wherein a relatively large number of adjustments may be readily obtained without materially weakening the spring shaft.

In the accompanying drawings:

40 Figure 1 is a side elevational view of a brush-holder constructed in accordance with my invention.

Fig. 2 is a plan view of a brush-holder frame with the brushes and spring removed 45 therefrom.

Fig. 3 is a view in side elevation of a brush spring shaft, illustrating the staggered position of the adjusting apertures.

Fig. 4 is an end view of the shaft illustrated in Fig. 3.

Referring to the drawings:

A brush-holder embodying my invention is illustrated as comprising an integral frame member 1, of any preferred construction or material. The frame 1 is provided,

at the forward end thereof, with a vertically disposed rectangular aperture 2 or box within which a carbon brush 3 is slidably mounted for vertical movement. A plurality of outwardly projecting lugs 4, provided with 60 apertures 5, are formed at the other end of the frame 1, preferably adjacent the corners thereof. Vertically extending insulated posts 6 are secured in the apertures 5 by means of pins 7. The upper ends of 65 the posts 6 are rigidly clamped to the main casing or frame 8 of the machine by means of co-acting jaw members 9 and a bolt 10. The posts 6 are provided with insulators 11 adapted to increase the creepage distance 70 between the brush-holder and the casing 8 of the machine.

The frame 1 is formed with a substantially rectangular opening 12 having a bottom 13 and side walls 14, the latter of which 75 are provided with inwardly extending bosses or bearing members 15. The bearing members 15 are provided with a plurality of intersecting apertures 16 extending radially therethrough, and which are shown as being 80 disposed at 30° intervals apart. A stud shaft 17 is mounted for rotary adjustment in the bearings 15 and is also provided at each end thereof with a plurality of similar apertures 18 staggered with respect to each other 85 and adapted to alternately register with the apertures 16 and the bearings 15.

The shaft 17 is further provided in one end thereof with a slot 19 adapted to receive a screw driver or other suitable tool by 90 means of which the shaft 17 may be rotated to obtain the necessary adjustments. A cotter pin 20 extends through the apertures 16 and 18 of the bearings 15 and the shaft 17, respectively, and maintains the 95 shaft 17 against axial or rotary displacement in the desired adjusted position.

The shaft 17 is also provided with a longitudinally extending slot 21 in which is fixed the end of a spiral brush spring 22. 100 The other end of the spring 22 extends over and exerts a yieldable downward pressure against the brush 3. A flexible spring shunt 23 is preferably riveted to the spring 22, as indicated at 24, and which extends 105 downwardly and is soldered or otherwise suitably fixed in an aperture 25 in the bottom 13 of the frame 1.

As illustrated in Figs. 3 and 4 of the drawings, the apertures 18 in the shaft 17 are dis- 110

posed at 45° intervals, those at the one end of the shaft 17 being staggered with respect to the similar apertures at the other end thereof.

5. By this arrangement, the shaft 17 may occupy double the number of rotary positions, without weakening the shaft than if the apertures 18 were in alinement.

10. The same results may be obtained by utilizing a plurality of apertures in one bearing element only, and by reversing the position of the shaft 17.

What I claim as my invention is:

1. A shaft mounting comprising a bearing element having a recess therein, a shaft mounted on said bearing and provided with a plurality of apertures arranged in different planes, the apertures disposed in one plane being staggered with respect to those of the other, and means disposed in said bearing recess for engagement with the apertures in said shaft for maintaining the same in adjusted position.

2. A shaft mounting comprising a bearing element having a recess therein, a shaft mounted on said bearing and provided with a plurality of apertures arranged in parallel planes, the apertures disposed in one plane being staggered with respect to those of the other, and means disposed in said bearing recess for engagement with the apertures in said shaft for maintaining the same in adjusted position.

3. A shaft mounting comprising a bearing element having a recess therein, a shaft mounted on said bearing and provided with

a plurality of apertures disposed in different planes, the apertures in one plane being disposed out of alinement with respect to those of the other plane, and means disposed in said bearing recess for engagement with the apertures in said shaft for maintaining the same in adjusted position.

4. A shaft mounting comprising a bearing element, having a recess therein, a shaft mounted on said bearing element and provided with a plurality of groups of radially intersecting apertures, the apertures disposed in one plane being staggered with respect to those of the other, and means disposed in said bearing recess for engagement with the apertures in said shaft for maintaining the same in adjusted position.

5. A brush-holder comprising a frame, a brush carried by said frame, bearing members secured to said frame, a plurality of apertures in said bearing members, a spring support mounted in said bearings, a spring carried by said support for engagement with said brush, a plurality of recesses in said support arranged in different planes and in staggered relation with each other and adapted to be caused to register with the openings in said bearings, and means disposed within said apertures and recesses for maintaining said support in an adjusted position.

In testimony whereof I have hereunto subscribed my name this 7th day of September, 1920.

JOHN S. DEAN.
